Attorney.

UNITED STATES PATENT OFFICE

MCLENNEN C. SLATE, OF ALBANY, OREGON, ASSIGNOR TO SLATE CONSTRUCTION COMPANY, OF ALBANY, OREGON

APPARATUS FOR CONTROLLING SCRAPERS

Application filed July 20, 1929. Serial No. 379,751.

The object of my invention is to provide a novel apparatus for controlling the operation of a scraper and also for permitting of its control from a distance, as from the seat of a tractor, by means of cords connected with the apparatus itself, and it is an object of my invention to provide novel means for adjusting the apparatus, and for mounting the operating lever, and for releasably locking same when operated.

I attain these and other objects of my invention by the apparatus illustrated in the accompanying drawings, in which—

Figure 1 is a side elevation of my invention, with dotted line showing one of the operative positions of lever 3; and

Figure 2 is a top plan view of my invention.

Like numerals designate like parts in each of the several views.

Referring to the accompanying drawings, I provide a scoop or scraper body or box 1, having a cutting blade 2, formed or mounted on its bottom plate member. I provide a tongue 4, provided with a slotted portion in which the slide 7 travels and to which slide is attached the three pulling rods 6, two of which have their outer ends connected with the side of the scraper and the third, and middle, rod engaging a pin 9 which forms the axis about which the scraper body turns.

At the rear of the body of the scraper, I provide posts 14 extending to a point substantially above the body of the scraper, and having a pin 10 positioned some distance below the upper end of the posts and extending through a slot 11 in the enlarged rear portion of the tongue 4 and limited in movement to said slot by the stop 19. The upper ends of posts 14 are provided with a pin 15 which engages in a slot 21 in the ends of spaced parallel links 13. Each of these links 13 is made in sections and is adjustable as to length by means of suitable slots and bolts as illustrated in Fig. 1. The forward ends of the links 13 are pivotally connected by the pivot or bolt 16 to the operating lever 3, which is formed or made in two sections in its lower end and pivotally mounted at 12 to the tongue 4 or members affixed to said tongue 4.

The upper and free end of the lever 3 is

provided with a rope 5 which runs under a suitable pulley 30 and extends forward any desired distance, as for example, to the seat of a tractor ahead, for operating the scraper.

I also provide a lever 23 pivotally mounted at 24 on the tongue 4 and held in its normal substantially vertical position by spring 25. This lever is provided with a lug 26 positioned to be engaged by a catch or projection 22 on the lever 3 when the latter is pulled to its most forward position.

I also provide a suitable pull cord 27, attached to the free end of lever 23 by which the latter may be operated to disengage it from operative connection with the catch 22 to release the lever 3 in accordance with the designs of the operator.

I prefer to provide shoes 20, as shown in Fig. 1 and Fig. 2, attached to the forward ends of the sides of the scraper. I provide a lever 17 on the forward end of the tongue 4 of the scraper, this lever 17 being arranged to operate spring control catch 8 and disengage it from slide 7 to release the latter member. A suitable pull cord 28 is attached to the free end of lever 17. I provide a suitable stop member 18 on the under side of tongue 4 spaced substantially distant from the end of the tongue, to limit the forward movement of tongue 4 and thus control or limit the range of tilting or swinging movement of the scraper.

Particular attention is called to the extension of posts 14 to a point substantially above the top of the scraper, and above the pivot 10 to which the end of the tongue 4 is connected, thereby providing means for connecting the links 13 to the bolt or pivot 16 of the operating lever 3, which arrangement makes possible the functioning of the operating lever in the manner illustrated and described.

In operation, as slot 21 is not long enough to accommodate all of the forward movement of pin 15, the links 13, pin 16, and lever 3 will move forward into the position shown in dotted lines in Fig. 1, when lever 3 is operated. The lower part of lever 3, as shown in Fig. 2, is made of branching mem-

bers and one of these branching members is provided with the catch 22 which as the lever travels forward strikes lever 23 which is pivoted at 24, thereby causing the lever 23 to swing forward against the pressure of spring 25 and allowing the catch 22 to engage under the lug 26 of lever 23. Spring 25 will again expand, moving lever 23 to its original position. Lever 3 will then be held in position shown by dotted lines until lever 23 is moved forward by a pull being exerted on rope 27. If before a pull is exerted on rope 27 the cutting blade 2 is again placed in contact with the earth by reversing the draft 10 means a few feet, the body of the scraper is caused to return through the same 90 degrees it turned in getting onto shoes 20. So long as lever 3, by means of catch 22 is being engaged with lug 26, lever 3 is held in a 15 position shown by dotted lines, the entire weight of the machine is on the cutting blade 2 and the loading operation of earth into the body of the scraper will continue. When sufficient earth has been loaded into the 20 scraper a pull on rope 27 will release lever 3 and allow the body of the scraper to tilt backward, thus allowing pulling rods 6 to slightly lift cutting blade 2 from the ground. The load is then hauled to a point where it 25 is desired to deposit it. A pull on rope 28 will cause the dumping action to take place and consequently lever 3 will be returned to the loading position so that when cutting blade 2 is returned into contact with the 30 earth loading may be continued without attention of the operator. Links 13 are each made in two pieces and by means of extra sets of holes may be lengthened or shortened at will by simply changing the bolts.

35 When lever 3 is in the position indicated by the dotted lines, pin 16 is only very slightly above point 12. This allows lever 3 to be held in above stated position without undue pull being exerted on lug 26 in lever 23. The fact that pin 16 is slightly above 40 point 12 will allow lever 3 to return toward the rear when released from notch 26. Still another feature is the fact that rope 5 may be entirely removed if desired. However, if 45 the machine is to be used for leveling rough or uneven ground, lever 23 could be removed or held in a forward position by rope 27 and lever 3 operated entirely by rope 5 at will of the operator. This is particularly ad- 50 vantageous where a small portion of a load is to be removed at several different points.

What I claim is:

1. In an apparatus of the class described, the combination of a scraper body, posts at 55 the rear of the scraper body said posts extending substantially above the top of the scraper body, a draft device having a pivotal connection with the said posts at a point spaced from the top portion thereof, a scraper operating lever mounted on the draft de-

vice, links operatively connected with the upper end of the posts and substantially above the top of the scraper said links having their forward end pivotally connected to the aforesaid operating lever whereby the lever 70 is moved to a forward position it will tilt the scraper, a rope attached to the free end of the operating lever, and a pulley mounted on the draft device over which the cord is threaded whereby a pull on the cord will 75 move the operating lever to its forward position to tilt the scraper to permit of operating the device from a distance.

2. In an apparatus of the class described, the combination of a scraper body, posts at 80 the rear of the scraper body, said posts extending substantially above the top of the scraper body, a draft device having a slideable and pivotal connection with the said posts at a point spaced from the top portion thereof, 85 a scraper operating lever mounted on the draft device, links operatively connected with the upper end of the posts and substantially above the top of the scraper said links having their forward end pivotally connected 90 to the aforesaid operating lever whereby when the lever is moved to a forward position it will tilt the scraper, a catch member on the operating lever, a spring pressed latch lever having a lug releasably engaging the 95 catch on the operating lever to hold the said lever in its forward position, and a cord attached to the free end of the latch lever to permit of operating the same from a distance.

3. In an apparatus of the class described, the combination of a scraper body, posts at 100 the rear of the scraper body said posts extending substantially above the top of the scraper body, a draft device having a pivotal connection with the said posts at a point spaced from the top portion thereof, a scraper operating lever mounted on the draft device, links operatively connected with the upper end of the posts and substantially 105 above the top of the scraper said links having their forward end pivotally connected to the aforesaid operating lever whereby when the lever is moved to a forward position it will tilt the scraper, a catch member on the oper- 110 ating lever, a spring pressed latch lever having a lug releasably engaging the catch on the operating lever to hold the said lever in its forward position, and a cord attached to the free end of the latch lever to permit of oper- 115 ating the same from a distance.

4. In an apparatus of the class described, the combination with a scraper body, of a post at the rear thereof, said post extending a substantial distance above the top of the 120 scraper body, a draft device having a pivotal connection with said post at a point spaced from the top portion thereof, a scraper operating lever mounted on the draft device, and a link connected with the upper end of the 125

post at a point spaced a substantial distance above the connection of the draft device with the post, said link having its forward end pivotally connected to said operating lever whereby when the lever is moved to a forward position it will tilt the scraper.

5. In an apparatus of the class described, the combination with a scraper body, of a post at the rear thereof, said post extending 10 a substantial distance above the top of the scraper body, a draft device having a slidable and pivotal connection with said post at a point spaced from the top portion thereof, a scraper operating lever mounted on the draft 15 device, and a link pivotally and slidably connected to the upper end of the post at a point spaced a substantial distance above the connection of the draft device with the post, said link having its forward end pivotally connected to said operating lever whereby when the lever is moved to a forward position it 20 will tilt the scraper.
